COMBINATION PEANUT ROASTER AND DISPLAY WARMER

Arthur D. Altemiller, Affton, Mo., assignor to Hercules Steel Products Corporation, Galion, Ohio, a corporation of Delaware

Application December 9, 1954, Serial No. 33,462

Term of patent 14 years

(Cl. D81—10)

Fig. 1.

Fig. 2.

Fig. 4.

Fig. 3.

The other end of the article is substantially plain.

I claim:

The ornamental design for a combination peanut roaster and display warmer, substantially as shown and described.
